CLAIM

The ornamental design for an engine, as shown and described.

DESCRIPTION

FIG. 1 is a left side frontal perspective view of the engine; FIG. 2 is a right side frontal perspective view of the engine; FIG. 3 is a left side rear perspective view of the engine; FIG. 4 is a right side rear perspective view of the engine; FIG. 5 is a front view of the engine; FIG. 6 is a rear view of the engine; FIG. 7 is a top view of the engine; FIG. 8 is a bottom view of the engine; FIG. 9 is a left side view of the engine; and, FIG. 10 is a right side view of the engine. It should be appreciated that the broken lines of FIG. 5 illustrate portions of the engine that form no part of the claimed design.
